WAGON

Francis Patrick McGuire and Henry Joseph
Oraschuk, Toronto, Ontario, Canada

Application May 31, 1949, Serial No. 2,968

Term of patent 14 years

(Cl. D34—15)

To all whom it may concern:

Be it known that we, Francis Patrick McGuire and Henry Joseph Oraschuk, British subjects residing at the city of Toronto, in the county of York, Province of Ontario, Canada, have invented a new, original, and ornamental Design for Wagon, of which the following is a specification, reference being had to the accompanying drawings, forming a part thereof.

In the drawing:

Figure 1 is a perspective view of a wagon showing our new design.

Figure 2 is a side elevational view of the same.

The characteristic features of the design of our wagon are shown in full lines in the drawing.

We claim:

The ornamental design for a wagon, as shown and described.

FRANCIS PATRICK McGUIRE.
HENRY JOSEPH ORASCHUK.
